(57) CLAIM

The ornamental design for a dish as shown and described.

DESCRIPTION

1. Dish

1.1 : Front

1.2 : Perspective

The subject of this design is a dish. The dish is round with high sides rising from the base. At the top of the dish close to the opening, there is a rim diameter that is slightly bigger than the body. There are geometric embossed patterns on the outer surface of the sides.
